UNITED STATES PATENT OFFICE.

JOHN BONNER SEMPLE, OF SEWICKLEY, PENNSYLVANIA.

TRACER FOR PROJECTILES.

1,077,204.

Specification of Letters Patent.

Patented Oct. 28, 1913.

Application filed November 20, 1912. Serial No. 732,543.

To all whom it may concern:

Be it known that I, JOHN B. SEMPLE, residing at Sewickley, in the county of Allegheny and State of Pennsylvania, a citizen 5 of the United States, have invented and discovered certain new and useful Improvements in Tracers for Projectiles, of which improvements the following is a specification.

10 My invention relates to ignition devices for tracer charges carried in projectiles. The object of my invention is a percussion ignition device, operated by the explosion of the propelling charge, which shall be at 15 once secure against chance operation, effective to protect the charge of tracer material against a sudden influx into the charge-containing chamber of the gases of explosion when the projectile is fired from a gun, 20 and which shall contain provision against the generation of a dangerous degree of pressure in the charge-containing chamber after firing and before the projectile leaves the muzzle of the gun. These and other advantages will be appreciated by those practising my invention.

I have discovered these essential features of a successful tracer-ignition device. First, if the chamber which contains the charge of 30 tracer material be otherwise open to the gases of explosion of the projectile-driving charge, a perfect gas-seal must be provided in the mouth of that chamber; second, the ignition device must certainly function at 35 the proper time, and certainly not function prematurely; and, third, if the ignition device is operated by the explosion of the projectile-driving charge, means must be provided to delay the too rapid burning of the 40 charge while the projectile is still in the gun.

In the accompanying drawings, Figure 1 is a view in longitudinal section of a projectile provided with a chamber for a charge of tracer-material, a charge therein, and an 45 ignition device, and embodying my present invention; Fig. 2 is a like view on larger scale of the stock in which the tracer charge is contained, detached from position in the body of the projectile. (In many instances 50 it is preferable, though by no means essential, to provide such a stock as a separate and detachable member; but it will be understood that the chamber for the charge of tracer material may be formed in the projectile itself.) Figs. 3 and 4 are views simi-

lar to Fig. 2, but illustrate various modifications in detail which may be resorted to. The showing afforded by these supplementary figures is not intended to be exhaustive, and it will be understood that they serve 60 merely to indicate some permissible variations in structure.

Referring to Figs. 1 and 2, the projectile 1 will be seen to be equipped with a tracer, this tracer consisting of a charge of combustible material *a*, contained in and located at the anterior end of a chamber 2 which is formed in a stock set in the body of the projectile. The mouth of this tracer chamber is (but for the presence of the apparatus about to be described) open and exposed to the impact of the gases of explosion of the charge which propels the projectile. This body of combustible material within chamber 2 is provided to burn during 75 the flight of the projectile, and as it burns to afford means by which the shell may be followed with the eye in its flight.

In the mouth of the chamber 2 are arranged an ignition device, and, coöperating therewith, a gas seal. The ignition device is of the percussion type, and is caused to operate by the pressure of the gases generated on the explosion of the projectile-propelling charge. Specifically, the ignition device 80 consists essentially of a box-like structure, formed of such material and of such proportions as to be rigid and to resist all stresses incident to handling previous to the firing of the projectile, but collapsible under the 85 relatively great stress of firing, and by collapsing, exploding a percussion cap properly exposed to ignite the tracer charge itself. In Figs. 1 and 2 the ignition device 90 consists of an anvil-member 3 and a hammer-member 4. The anvil-member consists of a block of metal arranged rearward of the charge of tracer material within chamber 2; it is provided with a dished or hollowed-out rear face, with a seat for a percussion cap in the center of its posterior dished face, and with a port 5 beneath the percussion-cap seat which gives access for 100 the flash of the exploding cap to the tracer charge itself. The hammer-member 4 is a 105 steel disk arranged rearward of the anvil member, its periphery resting against the periphery of the dished-out posterior face of the anvil-member; the hammer-member is provided with a pin 6 centrally arranged 110

on its anterior face, and the disk itself is of such thickness that, while under all ordinary conditions it is rigid, under the enormous pressure of the firing charge it is crushed against the dished-out face of the anvil-member, and its pin then impinges upon and explodes the percussion cap seated in the anvil-member. The collapsible ignition device is the same in all its parts in Fig. 3. In Fig. 4 there are coöperating anvil and hammer members, but, in their functioning, the rearmost of the two members, instead of being distorted and crushed against a hollowed-out face of the member opposed to it, moves forward as a rigid whole to fire the percussion cap. In this instance there is provision against forward movement of the rear member, effective under all ordinary conditions, but ineffective to prevent movement under the enormous stress of the firing of the projectile. This provision is found in the collapsible spacing ring 7.

Comparing Figs. 2 and 4, it will be observed that either the anvil-member or the hammer-member may be the anterior and relatively stationary member, and the other the posterior and movable member.

The gas seal is arranged rearward of the ignition device, and is so disposed and proportioned with relation to the ignition device that, while performing its purpose and effectually protecting the charge of tracer material from ingress of the gases of explosion of the projectile-propelling charge, it will still yield to allow the operating strain to be imparted to the ignition device. It consists preferably (Fig. 2) of a disk or wad 8 of suitable relatively plastic material (preferably lead) and of proper thickness, filling the mouth of chamber 2 immediately rearward of the ignition device, and having its edge intimately engaging, by being pressed tightly against the chamber wall or otherwise; and, of a cupped disk 9 (preferably of copper) arranged rearward of the disk of lead, resting against said lead disk and flaring rearwardly. This cupped disk 9 is spun or otherwise forced into the mouth of chamber 2. As shown in Fig. 4 the cupped disk 9 may be omitted, the bore of chamber 2 may be ungrooved, and the gas seal may consist merely of a disk or wad 11 of suitable material, preferably lead; the rear face of this disk will preferably be dished. As shown in Fig. 3, the gas seal may take the form of a cap 10 of suitable material (preferably copper) spun or otherwise applied to the rear of the tracer stock, the material being of such nature and the thickness being such as still to permit the ignition device to function. The effectiveness of this form of seal will be in some degree dependent upon the mode of application and the length of margin overlapping

the outer surface of the tracer stock; its peculiar advantage resides in the economy in space which it affords.

In the use of the ignition device which I have described above, I have found it necessary to provide against generation, within the tracer chamber and after firing and while the projectile is still in the gun, of a pressure so great as to injure or destroy the tracer charge or cause it to explode. The material which forms the tracer charge is, under normal conditions, combustible and slow-burning, but is none the less liable to explosion, or at least to sudden and substantially complete destruction, when ignited under great pressure. Inasmuch as the usefulness of a tracer lies in having the tracer-material burn with relative slowness while the projectile flies, it is necessary to see to it that the tracer material when ignited shall not be subjected to dangerous pressure. When the material is ignited, gases are formed, and if combustion proceeds in a closed chamber initially filled full of material, the pressure of confined gases of combustion will soon reach the critical point when sudden decomposition or explosion will ensue. I have heretofore proposed to guard against sudden decomposition or explosion of the tracer material by providing a body of slow-burning material, forming the posterior part of the charge of the tracer material as a whole which, ignited immediately on the firing of the gun, will burn so slowly that the tracer material proper will not be ignited under conditions such as to cause its premature destruction, but I am free to confess that I have not up to this time succeeded in finding and applying a material whose slow-burning nature is such as to make it effective for this purpose without a certain percentage of failure.

My present invention lies in provision against the generation of such a critical pressure as I have alluded to, in the chamber 2, after the ignition device has operated and while the projectile is still in the gun. To this end, my present invention consists in providing in the assembling of the parts a space *b* rearward of the charge of tracer material *a* in the chamber 2 and forward of the ignition device proper. This space *b* may be left empty—*i. e.* filled with air at atmospheric pressure—or (as is indicated in Fig. 3) it may be filled with a combustible material capable of ignition from the percussion cap and of imparting ignition to the body of the tracer charge, and itself in its ignition generating no substantial quantity of gas to cause a rise of pressure. Such a material is found in a mixture of lead oxid (PbO₂) and pure magnesium, which is combustible, and whose products of combustion (MgO and PbO) are solids. The presence of such a combustible filler of

neutral effect in those particulars under consideration may be advantageous under certain conditions, where the composition of the tracer material may suggest the desirability of such a space-filling primer material.

5 In order that I may the more certainly control the rapidity of initial ignition, or eliminate the chances of erratic behavior in functioning, I preferably employ (in case the space *b* is left vacant—see Fig. 2) a shield 12 partially covering the posterior face of the body of tracer material *a* within the tracer chamber. Preferably this shield 12 fills the bore of the chamber and is provided with a central perforation. Through 10 this perforation the flash of the exploding ignition cap will have access to the otherwise shielded rear surface of the body *a*; and thus, while the area of initial ignition is reduced, the extent of initial ignition will be subject to less variation. This perforated shield 12 may be made of cardboard, and in 15 assembling it may be carried to place upon the body of tracer material by a drift bearing a point corresponding in position to the location of the perforation in disk 12; this pointed instrument will insure clearance from the perforation of any burred edge which might otherwise close the perforation 20 wholly or in part. The effect of the point-bearing drift is indicated in the drawing by the shaping of the body of tracer material immediately beneath the perforation in disk 12.

25 Comparing Figs. 2 and 3, it will be observed that whereas the bore of chamber 2 is offset to afford a shoulder against which the anvil block 3 may abut in its proper functioning, the bore of the chamber is, in Fig. 3, smooth, and there is no such shoulder for the abutment of the anvil-block, but in this instance the space *b* is filled with 30 such a neutral material as I have heretofore indicated. In this case the body of neutral material itself is a body against which the anvil-block 3 abuts, in order that it may function. In this particular the structure of Fig. 3 is simpler than that of Fig. 2, and the use of the neutral filler 35 material is in this respect advantageous.

40 The advantages of my present invention will be clearly understood with a few additional words of explanation. It will be appreciated that when the projectile passes from the muzzle of the gun from which it 45 has been fired, the pressure at the rear, which has up to that point been relatively enormous, and which has imparted to the projectile its speed, is suddenly cut off and thereafter as the projectile flies, the pressure is (relatively speaking) substantially atmospheric pressure or less; and the further fact will be appreciated that, after the projectile 50 equipped with the tracer leaves the gun, the pressure generated in the tracer chamber 55

60 by the ignition then in progress, though utterly inconsiderable in comparison with the enormous pressure of the propelling charge, is sufficiently great to drive from the mouth of the tracer chamber the ignition device and the gas seal together, so that thereafter as the projectile flies, the tracer material will burn freely from its open-mouthed chamber. If the chamber 2 65 were entirely filled with tracer material of such character as I ordinarily employ, ignition being effected immediately on firing, there would be danger that, before the projectile had passed from the muzzle of the gun, the critical pressure indicated above would have 70 been reached within chamber 2; but, by providing the space *b*, either vacant or filled with a neutral material of the nature indicated, the rate at which pressure will rise 75 within chamber 2 in response to the burning of the charge will be very appreciably delayed, and it is a matter of proper proportioning of parts and the size of the charge in view of the nature of the material used, to insure against the generation of the critical pressure before the projectile has passed 80 from the muzzle of the gun. After the projectile leaves the gun, the danger ceases to exist, as will be understood from the foregoing explanation. 85

90 I claim as my invention:

1. A projectile provided with a tracer chamber open-ended to the gases of explosion of the propelling charge, a body of tracer material within said chamber, and 100 a percussion ignition device, operable directly by the pressure of the propelling gases arranged in the mouth of the said chamber, a space being left between the body of tracer material within said chamber 105 and the ignition device in the mouth thereof.

2. A projectile provided with a tracer chamber open-ended to the gases of explosion of the propelling charge, a body of 110 tracer material within said chamber, an ignition device arranged in the mouth of the said chamber, a space being left between the body of tracer material within said chamber and the ignition device in the 115 mouth thereof, and a shield covering all but a predetermined portion of the posterior face of the body of tracer material within said chamber.

3. A projectile provided with a tracer chamber open-ended to the gases of explosion of the propelling charge, a body of tracer material within said chamber, an ignition device arranged in the mouth of the said chamber, a space being left between the body of tracer material within said chamber and the ignition device in the mouth thereof, and a body of material combustible without generation of substantial 120 quantities of gas filling said space. 125

4. A projectile provided with a tracer chamber open-ended to the gases of explosion of the propelling charge, a body of tracer material within said chamber and occupying the anterior portion thereof, a percussion ignition device operable directly by the pressure of the propelling gases arranged in the mouth of said chamber, a space interval being left rearward of the said body of tracer material and between said ignition device, and a gas seal arranged rearward of said ignition device.
5. A projectile provided with a chamber open-ended to the gases of explosion of the propelling charge and containing a charge of tracer material occupying the anterior portion thereof, a perforate anvil-block provided with a dished posterior face and spaced at an interval rearward of the said body of tracer material, a hammer member arranged rearward of said anvil member, and a gas seal arranged rearward of said hammer member and filling the mouth of said tracer chamber.
6. A projectile provided with a chamber open-ended to the gases of explosion of the propelling charge, a body of tracer material occupying the anterior portion of said tracer chamber, an ignition device arranged within said chamber and spaced at an interval rearward of said body of tracer material, a disk of relatively plastic material intimately engaging the bore of the tracer chamber rearward of said ignition device and a second disk of relatively rigid material arranged rearward of said plastic disk and filling the mouth of said tracer chamber.
7. A projectile provided with a chamber open-ended to the gases of explosion of the propelling charge, a body of tracer material occupying the anterior portion of said tracer chamber, an ignition device arranged within said chamber and spaced at an interval rearward of said body of tracer material, a disk of relatively plastic material intimately engaging the bore of the tracer chamber rearward of said ignition device, and a second disk of relatively rigid material arranged rearward of said plastic disk and filling the mouth of said tracer chamber, and a partial covering over the posterior face of the body of tracer material, limiting the area of ignition.

In testimony whereof I have hereunto set my hand.

JOHN BONNER SEMPLE.
